[57] CLAIM

The ornamental design for a refrigeration gauge manifold bracket, substantially as shown and described.

DESCRIPTION

FIG. 1 is a front elevation of the refrigeration gauge manifold bracket showing our new design;

FIG. 2 is a rear elevation thereof;

FIG. 3 is a top plan thereof;

FIG. 4 is a bottom plan thereof; and

FIG. 5 is a side elevation thereof, the opposite side elevation being a mirror image.

FIG. 1

FIG. 2

FIG. 3

FIG. 4

FIG. 5
